UNITED STATES PATENT OFFICE.

THOMAS A. REID, OF PITTSBURGH, PENNSYLVANIA, ASSIGNOR TO WESTINGHOUSE ELECTRIC & MANUFACTURING COMPANY, A CORPORATION OF PENNSYLVANIA.

METHOD OF SUPPORTING RESISTOR MOUNTING PLATES.

Application filed March 30, 1921. Serial No. 456,830.

To all whom it may concern:

Be it known that I, THOMAS A. REID, a citizen of the United States, and a resident of Pittsburgh, in the county of Allegheny 5 and State of Pennsylvania, have invented a new and useful Improvement in Methods of Supporting Resistor Mounting Plates, of which the following is a specification.

My invention relates to electric furnaces 10 and particularly to electric resistance furnaces and it has for its object to provide a relatively simple and easily manufactured heating-unit supporting means.

In practicing my invention, I provide a 15 furnace chamber with a lining comprising a plurality of refractory members, each member being substantially of overhung channel section and providing a means for holding a flat resistor-supporting member and its 20 associated resistor element.

Referring to the single sheet of drawings:

Figure 1 is a view, in lateral cross-section, of an electric furnace comprising the device embodying my invention;

Fig. 2 is a view, in end elevation, of the device embodying my invention with an associated heating unit;

Fig. 3 is a view, in end elevation, of a modified form of the device embodying my 30 invention with an associated heating unit, and

Fig. 4 is a view, in side elevation, of a heating unit which is to be operatively associated with the device embodying my 35 invention.

The heating unit hereinafter referred to more in detail and illustrated in Fig. 4, constitutes the subject-matter of a joint application of O. A. Colby and myself, Serial No. 40 449,685, filed March 5, 1921, the assignee of which is the same as that of the present application.

An electric resistance furnace 1, comprises an outer metallic framework or casing 2 supported on suitable standards 3. An inner lining 4 of suitable refractory heat-insulating brick is located in the casing 2, the bricks comprising the lining 4 being so spaced apart as to form a suitable chamber 5.

A plurality of heating-unit supporting members 6 are located inside of the lining 4, each of which comprises a refractory member substantially rectangular in contour and of any desired or suitable material and thickness to withstand not only the relatively high

temperature to which it will be subjected, but also to possess sufficient mechanical strength. The members 6 may be described as being of overhanging channel-section in lateral cross section or as comprising a member having a relatively shallow, wide, and partially enclosed channel or depression 7 in one face or surface thereof and overhanging portions 8; the said overhanging portions being oppositely spaced relatively to 60 each other.

A resistor-supporting member 9 comprises a relatively thin refractory plate substantially rectangular in contour having a plurality of spaced and alined projections 10 70 on one surface thereof, the spacing and alinement of the projections 10 being such as to permit of a resistance element 11 being located on one surface of the plate 9 and held in operative position thereon by means of 75 the projections 10. The resistor element 11 comprises suitable resistance metal of relatively large cross-sectional area, so as to make it possible to form the same to the shape illustrated in Fig. 4 before it is placed 80 on the plate 9.

The width of the channel 7 is slightly greater than the width of the plate 9 and the heating unit, substantially as illustrated in Fig. 4 of the drawing, may be placed in its 85 operative position relatively to the member 6 by sliding the plate and the resistor element 11 laterally into the channel 7 the projections 8 serving to hold the members in the position illustrated in Figs. 1 and 2. 90

The furnace illustrated in Fig. 1 combines a plurality of heating-unit supporting members 6 located at the side walls and at the top wall of the furnace. The members 6 at the sides of the furnace are substantially 95 of the shape illustrated in Fig. 2 while the members 6 used in the top wall of the furnace are slightly modified at their edges to permit of a plurality of members 6 being combined to form a self-supporting arch 100 member. Suitable slabs or bricks 12 and 13 are provided to form a part of the roof of the furnace and to cooperate with the members 6 at the top to form a supporting means for the arch. The shape of the members 12 105 and 13 is for illustrative purposes only as they may be made of any required shape to perform their intended function.

Fig. 3 illustrates a modified form of the heating-unit supporting member which com- 110

prises a refractory member 14 provided with a channel portion 15, this channel portion being somewhat wider than the channel portion 7 in the member 6. The distance between the opposing overhanging portions 8 in the member 14 is less than the width of the plate 9 to permit of inserting the plate 9 and the resistor element 11 in a manner indicated by the broken lines in Fig. 3. The plate 9 is so held relatively to the member 14 as to permit of sliding the upper edge of the plate 9 back of the upper overhanging portion 8, and of so moving it upwardly as to permit of the lower edge of the plate 9 clearing the upper edge of the lower overhanging portion 8. The plate 9 may now be so moved as to cause it to lie substantially parallel to the inner surface of the member 14 after which it may be dropped to the position indicated by the full lines of Fig. 3. The modified form of the heating-unit supporting member thus permits of quickly removing a damaged plate or one in which the resistor element 11 has become damaged and of quickly replacing it by a new plate and resistor element without the necessity of disturbing or of removing any other of the members 14.

It may be noted that the bottom heating units in the furnace comprise only members 9 and the associated resistor elements 11, but this is not essential as I may use either members 6 or 14 for the floor of the furnace, in the same manner as indicated in Fig. 1 for the other walls of the furnace chamber.

It may be noted that the device embodying my invention provides a relatively simple and easily manufactured heating-unit supporting means as well as providing a lining for the furnace chamber. By the use of the modified form of the device embodying my invention, I provide a heating unit supporting member which permits of quick and easy removal of a damaged heating unit and its quick replacement.

Various modifications may be made in the device embodying my invention without departing from the spirit and scope thereof and I desire that only such limitations shall be placed thereon as are limited by the prior art or are specifically set forth in the appended claims.

I claim as my invention:

1. In an electric resistance furnace, in combination, a plurality of refractory walls enclosing a furnace chamber, a plurality of refractory supporting members, the lateral cross-section of which is of substantially overhung-channel shape, the overhanging portions being of unequal length, and a heating unit, supported by each of said over-

hanging portions, comprising a relatively thin plate substantially narrower than said channel, and a resistor unit supported by said plate, said plate being placed in operative position by a lateral and tilting movement thereof.

2. In an electric resistance furnace, in combination, a plurality of refractory walls enclosing a furnace chamber, a plurality of refractory supporting members, the lateral cross-section of which is of substantially overhung-channel shape, the overhanging portions being of unequal length, and a heating unit, supported by each of said overhanging portions, comprising a relatively thin plate substantially narrower than said channel and a resistor unit supported by said plate, said plate being placed in proper operative position by first placing one lateral edge under an overhanging portion and then placing the other lateral edge under the other overhanging portion.

3. In an electric resistance furnace, in combination, a plurality of refractory walls enclosing a furnace chamber, a plurality of refractory supporting members, the lateral cross-section of which is of substantially overhung-channel shape, the overhanging portions being of unequal length, and a heating unit, supported by each of said overhanging portions, comprising a relatively thin plate substantially narrower than said channel and a resistor unit supported by said plate, each of said thin refractory plates being selectively placeable in proper operative position by first moving one lateral edge under an overhanging portion and then placing the other lateral edge under the other overhanging portion.

4. In an electric resistance furnace, in combination, a plurality of refractory walls enclosing a furnace chamber, a plurality of refractory supporting members, the lateral cross-section of which is of substantially overhung-channel shape, the overhanging portions being of unequal length, and a heating unit, supported by each of said overhanging portions, comprising a relatively thin plate substantially narrower than said channel and a resistor unit supported by said plate, each of said thin refractory plates being selectively placeable in proper operative position by first moving one lateral edge under an overhanging portion and then placing the other lateral edge under the other overhanging portion and being selectively removable by a lateral and tilting movement thereof.

In testimony whereof, I have hereunto subscribed my name this 23rd day of March, 1921.

THOMAS A. REID.
